N. DAVIS.

CUTTER ATTACHMENT FOR SEWING MACHINES AND THE LIKE.

FILED JULY 20, 1920.

UNITED STATES PATENT OFFICE.

NATHAN DAVIS, OF DORCHESTER, MASSACHUSETTS.

CUTTER ATTACHMENT FOR SEWING MACHINES AND THE LIKE.

Application filed July 20, 1920. Serial No. 397,663.

To all whom it may concern:

Be it known that I, NATHAN DAVIS, a citizen of the United States of America, and a resident of Dorchester, in the county of Suffolk and State of Massachusetts, have invented a new and useful Cutter Attachment for Sewing Machines and the like, of which the following is a specification, reference being had to the accompanying drawing, forming part thereof.

The object of my invention is to provide a cutter attachment, more particularly for the so-called picot stitching sewing machines. The attachment is so associated with the stitching mechanism of the sewing machine as to lie directly in the path of travel of the advancing and stitched material passing the stitching point of the machine for engaging and cutting into said material to sever the connecting strands of the same between the rows of hemstitching forming the so-called picot edge, thus effecting the cutting operation automatically and simultaneously with the stitching operation of the machine.

It is a known fact in the dressmaking art that picot edging is used to a considerable extent in the manufacture of dresses and ladies' attire, and that ordinarily the picot stitching operation is done by the sewing machine, while the cutting operation, for which my invention is particularly intended, is done separate and by hand. The latter operation, besides being an expensive one, does not yield a uniform finish to the picot edge; while on the other hand, a uniformly cut picot edge is afforded the material through the application of the within device which eliminates the expense attending the aforesaid hand cutting operation.

To these as well as other ends my invention consists of the novel features of construction, combination and arrangement of parts described in the following specification and particularly pointed out in the subjoined claims.

The terms employed herein are used in the generic and descriptive sense to designate the elements illustrated, and are therefore not primarily intended as terms of limitation.

In order to illustrate my invention, I have shown in the accompanying sheet of drawing a single embodiment thereof, but without being limited thereto, wherein:

Fig. 1 represents a fragmentary eleva-

tional view of the presser-foot and stitching section of a picot stitching machine showing the same supplied with my cutter device;

Fig. 2 represents a sectional view taken on line 2—2 on Fig. 1;

Fig. 3 represents a right elevational view of Fig. 1;

Fig. 4 represents a sectional view taken on line 4—4 on Fig. 1;

Fig. 5 represents a plan view taken substantially on line 5—5 on Fig. 1;

Fig. 6 represents a sectional view taken on line 6—6 on Fig. 1;

Fig. 7 represents a sectional view taken substantially on line 7—7 on Fig. 5;

Fig. 8 represents a diagrammatic view of a piece of fabric removed from under the presser foot, showing the picot stitching and the cutting of the connecting strands as effected by the within cutter device;

Fig. 9 represents a perspective view of the cutter attachment removed from the presser foot of the machine;

Fig. 10 represents a perspective view of the stationary coating guide and cutter finger or blade of the within device removed from the table plate, or machine base, which supports the same;

Fig. 11 represents a miniature plan of the throat plate shown in the preceding views of the drawing; and

Fig. 12 represents a modified view of Fig. 4, showing the rotary cutter member of the device projecting into a recess provided therefor in the table plate.

Note that all of the views, with the exception of Fig. 11, are drawn enlarged to more clearly set forth the invention, said enlarged views being practically double the actual size of the mechanism exhibited herein.

Like numerals refer to like parts throughout the several views of the drawing.

The numeral 20 (Fig. 1) represents the reciprocating presser foot bar which carries 100 secured thereto the presser-foot 21. The latter at the lower end thereof forms a forked section, as indicated in Fig. 4, wherein 22 and 23 represent the arms which slidably fit within the slots provided therefor in the individual presser-foot runs 24 and 25, respectively, the latter being each pivotally coupled at 26 (Fig. 1) to said arms to yield a slight rocking play therebetween.

27 and 28 are the reciprocating stitching 110

needles which do the hemstitching in the machine and which are carried by the reciprocating members 29 operating in the head of the machine (not shown). 30 represents the hole punching plunger which is carried by the reciprocating plunger bar 31, which is also operated in the head of the machine (not shown). 32 represents the stationary throat plate (Fig. 11) which sets in flush 10 with the machine base 33 to which the same is secured, as shown in Fig. 1, and has the apertures 34 cut therein through which the material feeding and advancing ratchet plates 35 operate, as shown in Fig. 4, and 15 also has the openings 27', 28' and 30' to accommodate the reciprocating needles 27 and 28 and the hole punching plunger 30, respectively.

36 represents the cutter bracket which is 20 preferably slotted at 37 to fit the arm 23 of the presser-foot 21, and is provided with the clamp-screw 38 which securely clamps said bracket 36 in set position with said presser-foot. Said bracket 36 is further 25 provided with the projecting bearing lug 39 on which the cutter disc 40 is rotatably mounted and which is rotatably held on said bracket by means of the washer 41 and retaining screw 42 carried by said bracket 30 36. The cutter member 40 is provided with the annular knife edge 43 and the grooved collar section 44 which engages with the endless drive-belt or cord 45, as shown in Fig. 4. The latter drive-belt or cord 45 is coupled 35 in any suitable manner, preferably with a rotating element of the machine for rotating said cutter member 40. 46 represents a stationary, coacting cutter finger, or blade, which is designed with the knife-edge 47 40 setting adjacent to the cutter member 40, as shown in Fig. 4, for coacting with the latter to effect a shearing feature therebetween, as will be understood. Said cutter finger 46 is preferably rounded off at the 45 end 48 to serve as a guide for the material for ushering the same into the cutting position as it is being advanced through the machine while the stitching operation is taking place. 49 represents the base of said cutter finger, or blade, 46 which is preferably provided with the elongated countersunk holes 50, as shown in Fig. 10, which receive the anchoring screws 51 and which screws adjustably engage and secure said 50 cutter finger, preferably with the throat plate 32 by passing through the screw-threaded openings 50' therein, as shown in Figs. 1, 3, 5, 6, 7 and 11, in working relation with said cutter member 40; it being 55 here noted that the latter member is carried up and down with the presser-foot, wherefore it is desirable and preferable to make the depth of said cutter finger 46, particularly at the knife edge 47, sufficient to provide the adjacent contact with said cutter

member 40 when the presser-foot is raised to its highest position.

Fig. 12 shows a modification of the device wherein the throat plate 32 is slotted or recessed at 52 to receive the cutter member 40', as shown in said figure, when the presser-foot is set in its lower position, whereby the employment of the cutter finger or blade 46 is eliminated. This is made possible by suitably increasing the diameter of the cutter member 40, so that it enters the recess 52 provided therefor in the plate 32 as aforesaid. The table 32 itself thus assumes the function of the finger member 46, which is made possible wherever the design of the table plate 32 will so permit. As will be understood, the separate type of finger member 46, however, provides for the adjustable feature and also permits of the ready removal of the same from the table 85 plate for sharpening or replacing purposes, and eliminates the need for mutilating the plate 32 to provide the cutter recess 52 above described.

It will be here noted that the knife edge 90 43 of the cutter member may be positioned to assume the desired cutting plane, which in this case (see Fig. 5) is midway between the lines of hemstitching H of the material M for severing the connecting picot strands 95 S formed therebetween, and thus cutting the material M into two parts M₁ and M₂ as shown in Figs. 1, 5, 7 and 8.

Having thus described the parts of the invention in detail, it will here be noted that the same provides a simple but reliable and effective means for affording the cutting feature sought to be obtained thereby. The nature of the invention permits of its ready application to the standard types of 100 sewing machine mechanisms employed in doing the so-called picot stitching for effecting the cutting operation in connection therewith in the machine itself as rapidly as the stitching operation is being accomplished 105 therein. Because of that fact it is obviously apparent that the usual hand cutting operation of the already stitched material for severing the picot strands is entirely eliminated, whereby a consequent saving in labor 110 and time is assured, together with the advantage of a perfectly uniform finish to the picot edging, which is impossible to obtain in the hand cutting operation.

The within device, as will be understood, 120 may be made up as part of the machine mechanism direct, that is, integral or permanently associated therewith, whenever so required, notwithstanding the fact that the within disclosure particularly treats with a design 125 of device which is of a detachable nature. The latter feature, however, permits of flexibility of adjustment which is advantageous in many respects and also permits of the application of the invention to standard 130

types of machines already in use without requiring any change of same to associate the invention therewith.

The rotary cutter member 40 may be 5 power driven (as suggested by the endless belt 45 shown in the drawing, which belt may be coupled with any suitable driving means available therefor) or otherwise, it being understood that while the power 10 driven type of disc cutter will yield a more effective cutting feature to the device, yet an ordinary rotary disc type of cutter will also function without being power driven, since the disc cutter will be frictionally rotated by the engagement therewith of the 15 material to be cut thereby and consequently yields the sharing feature which provides for a perfect cutting operation.

In that regard it will be noted that a disc 20 cutter as herein disclosed, which is shown provided with a belt collar, may be operated either as a power driven cutter or as a frictionally driven cutter, according as may be desired, the latter being accomplished by the 25 simple disengagement of the belt therefrom.

It will be noted that so far as the operator is concerned, no extra work is required on the part of said operator in handling and working a machine supplied with the with- 30 in cutting device, in that the same guiding and feeding of the material to the machine for stitching purposes is all that must be cared for by the operator. The cutter mem- 35 ber of the device having the cutter elements thereof positioned in the desired plane and relatively close to the needles of the machine, receives the advancing and stitched material directly as it leaves said needles and while the material is still guided and held in ad- 40 vancing position under the presserfoot of the machine; wherefore no extra effort on the part of the operator is required to man- age and attend to the work of the within in- 45 vention, which work is accomplished auto- matically and simultaneously with the stitching and continues as long as material is allowed to engage and pass the same.

It will further be noted that the cutter 50 members may be sharpened or replaced as often as may be found necessary and that

the device does not in any way encumber the regular functioning of the machine when applied thereto.

While the preferred embodiments of my invention have been described in detail, it 55 will be understood that I do not wish to be limited to the particular construction set forth, since various changes in the form, material, proportions, arrangement of parts, and in the details of construction may be 60 resorted to without departing from the spirit and scope of the invention, or destroy- 65 ing any of the advantages contained in the same, heretofore described and defined in the subjoined claims.

Having thus described my invention in detail, what I claim as new is:

1. In combination with a picot stitching machine presser-foot and machine head base, a detachable bracket adapted to be detach- 70 ably secured to said presser-foot to be carried thereby; a disc cutter rotatably mounted on said bracket and adapted to operate in a vertical plane rearward of the stitching point of said machine and inter- 75 mediate the rows of stitching forming the picot work for severing the picot strands; and a coacting shearing member provided on said machine head base and adapted to engage with said disc cutter for severing the 80 material being advanced under said pres- 85 ser-foot.

2. In combination with a picot stitching sewing machine, a bracket member adapted to be attached to a leg of the presser-foot 85 thereof; a rotatable disc cutter mounted on said bracket and supported to operate in a vertical plane between the lines of hemstitching formed in the material operated on and advanced in said machine; and rearward of 90 the stitching point and a correlated member having a cutter edge provided in the table base of said machine for engaging with said disc cutter to effect a shearing action against said material when directed into 95 contact between the aforesaid cutter elements.

In witness whereof, I hereunto affix my signature this seventeenth day of July, 1920.

NATHAN DAVIS.
